Attorney

UNITED STATES PATENT OFFICE.

JOHN J. WAGNER, OF GREEN COVE SPRINGS, FLORIDA.

DRAFT-ACCELERATOR AND VENTILATOR.

1,285,487.

Specification of Letters Patent. Patented Nov. 19, 1918.

Application filed December 13, 1917. Serial No. 206,884.

To all whom it may concern:

Be it known that I, JOHN J. WAGNER, a citizen of the United States, residing at Green Cove Springs, in the county of Clay and State of Florida, have invented certain new and useful Improvements in Draft-Accelerators and Ventilators, of which the following is a specification.

This invention relates to smoke flues and 10 ventilators. It was devised with particular regard to army field ovens to overcome the poor draft conditions that prevail with the customary low stacks. It uses, however, are manifold and it is of especial utility as a 15 ventilator for apartments, elevators, ships, street cars, railway cars, etc. A distinct merit of the invention is that it provides for the dual function in a single structure, that is to say it is reversible so that in one position 20 it functions as a ventilator and in the reverse position it functions as a smoke flue and draft accelerator, all of which works for simplicity, economy and practicability.

The nature, characteristic features and 25 scope of the invention will more readily be understood from the following description, taken in connection with the accompanying drawings, wherein,—

Figure 1 is a perspective view of my im- 30 proved ventilator and draft accelerator.

Fig. 2 is a view principally in vertical section of the device of my invention positioned, equipped and arranged to function as a smoke flue or draft accelerator.

Fig. 3 is a sectional elevational view of 35 the device disposed as a ventilator; and

Fig. 4 is a section on line 4—4 of Fig. 2.

The main or body portion, air drum or 40 chamber 5, open at each end, is provided circumferentially with flaring or bell shape air injecting nozzles 6, the number of which may vary, but preferably four in number in order to take air from any quarter. Internally of the structure 5 and co-extensive 45 with the nozzles 6, there are air ducts 7, which are canted somewhat out of the per-

pendicular and discharge the inducted air in spiral or whirling fashion along or upon the inside wall of the part 5, either upwardly or downwardly according to how the latter 50 is disposed. In Fig. 1, the device is shown as a smoke flue and draft accelerator and is provided at the bottom with a basal or stack connecting part 8, which is relatively contracted for the major portion of its length 55 and merges on graceful lines with the air chamber; and the device is further provided at the top with a smoke discharging cover plate or cowl 9 which is telescopically or otherwise removably applied thereto. Evi- 60 dently the smoke and gases under forced or accelerated draft pass through the open dome 10 and are finally discharged under the overhang or skirt 11.

In Fig. 3 the device is shown in the reverse 65 position, stripped of the cowl of course, and with the air ducts 12 discharging downwardly for ventilating purposes. The contracted portion or neck 13, in this embodiment, acts as an eduction passage for foul 70 or vitiated air.

It will be obvious to those skilled in the art to which the invention relates that modifications may be made without departing from the spirit and scope of the invention. 75 Hence, the same is not limited other than required by the state of the prior art.

Having described the nature and objects of the invention, I claim:—

A device of the character stated, comprising the combination of an air drum, nozzles externally thereof and having conducting tubes penetrating the walls of the drum and disposed at substantially right angles to the nozzles, a stack connecting 80 85 member consisting of a constricted tubular part or neck, and means designed to coöperate with the drum whereby it is adapted to function either as a draft accelerator or ventilator. 90

In testimony whereof I affix my signature.

JOHN J. WAGNER.
